TENNIS RACKET FRAME

William Charles Carlton, Ardleigh, Essex, England, assignor to Carlton Sports Company Limited, London, England

Continuation of design applications Ser. No. 10,517, Feb. 9, 1968, and Ser. No. 10,836, Mar. 4, 1968. This application Dec. 10, 1968, Ser. No. 14,866

Claims priority, application Great Britain Dec. 7, 1967

Term of patent 14 years

Int. Cl. D21—03

U.S. Cl. D34—5

Fig. 2.

Fig. 1.

FIG. 1 is a front elevation of one form of the tennis racket frame showing my new design;

FIG. 2 is a side elevation of the frame of FIG. 1;

FIG. 3 is a front elevation of another form of the tennis racket frame showing my new design; and

FIG. 4 is a side elevation of the frame of FIG. 3.

This application is a continuation of applications Ser. Nos. D. 10,517 and D. 10,836, filed by me respectively on Feb. 9, 1968 and on Mar. 4, 1968.

I claim:

The ornamental design for a tennis racket frame, as shown and described.
